UNITED STATES PATENT OFFICE.

REINHARD MANNESMANN, OF REMSCHEID, GERMANY.

MANUFACTURE OF SEAMLESS TUBES.

SPECIFICATION forming part of Letters Patent No. 361,958, dated April 26, 1887.

Application filed March 28, 1887. Serial No. 232,793. (Model.) Patented in Belgium August 14, 1886, No. 54,857.

To all whom it may concern:

Be it known that I, REINHARD MANNESMANN, of Remscheid, Germany, have invented certain Improvements in Apparatus for Transforming Solid Billets or Bars of Metal into Seamless Tubes, of which the following is a specification.

In another pending application for a patent I have described a method of developing a tubular formation from a solid metallic blank by the employment of appropriately-adjusted diagonally-acting rolls or dies, the working-faces of which are abruptly convergent. The product produced by the said method is not tubular throughout, but is solid at one end. This solid portion has to be cut off when the method is employed for the manufacture of tubes.

The present invention, by which I effect the transformation of a solid ingot or blank into a hollow body or tube which is open from end to end, consists in the combination, with the diagonally-acting rolls, of a comparatively slender rod, which is contained within the tube in the process of formation and made to abut against and hold back the solid central portion of the blank, and to thus effectually oppose the tendency of the solid central portion to move forward under the influence of the external diagonally-acting rolls, the result being that the ingot or blank is transformed into a tube which is open from one end to the other. This method is especially useful for the manufacture of seamless tubing from solid blanks composed of iron or steel, which require to be very highly heated preparatory to being subjected to the action of the diagonal rolls.

As machines for diagonal rolling are well known, it is not deemed necessary to herein show or describe them, and the accompanying drawings therefore simply illustrate various stages in the transformation of an iron or steel blank into a seamless tube during its progress between the convergent faces of two diagonally-acting conical rolls, midway between which there is arranged a slender rod for at the proper time abutting against and holding back the solid central portion of the blank.

The blank is so proportioned in diameter

with reference to the angles of convergence and the width of the space between the working-faces of the diagonally-acting rolls that the tubular formation initiated by the action of the rolls will have a greater internal diameter than the diameter of the holding-back rod, and thus the end only of the holding-back rod will be in contact with the heated blank. 55

The drawings are as follows: Figure 1 affords a top view of a pair of conical rolls, the axes of which occupy parallel vertical planes, but are inclined in opposite directions from a horizontal plane, also showing a top view of the holding-back rod, which at one end is stepped or journaled in a standard or some stationary part of the machine and has its free end projecting into the narrower part of the space between the convergent working-faces of the rolls. Figs. 2, 3, and 4 are views similar to that shown in Fig. 1 of the diagonal 70 rolls and of the holding-back rod.

In the figures the blank and the product resulting therefrom are represented in central longitudinal section, respectively, soon after the commencement at two intermediate stages 75 and at the conclusion of the operation of transforming the solid blank into a tube open from end to end.

For the sake of simplicity in description, it is assumed that the blank in all cases travels 80 through a horizontal path between two diagonally-acting rolls which are respectively arranged on either side of it. The rolls A and B, which are slightly conical, so that their working-faces are slightly convergent, rotate 85 in the same direction, but their axes incline from the horizontal plane, respectively, in opposite directions.

For operating on iron or steel it is desirable that the working-faces of the rolls shall have 90 formed upon them spiral ribs, such as heretofore used, or that they shall be otherwise so corrugated or roughened as to enable them to take a more effective hold upon the surface of the blank. 95

In Fig. 1 the solid blank C (shown in longitudinal section) is represented as having been seized and carried so far through the space between the rolls that the tubular formation has been initiated, but the solid central portion of 100

the blank has not yet been carried far enough forward to be brought into collision with the blunt end d of the holding-back rod D. The end d' of the rod D is stepped in a stationary box, E, thus permitting the rod D to rotate upon its longitudinal axis, but supporting it so that by the abutment of its end d against the solid central portion of the blank C it is enabled to perform its function of holding back 10 the solid central portion of the blank.

Fig. 2 illustrates a further stage in the rolling operation, in which the tubular formation has been fully developed and the end d of the holding-back rod D is in contact with the solid 15 central portion, C', of the blank.

Fig. 3 represents a further advanced stage, at which, if desired, the holding-back rod may be removed, in which case the product will be 20 a tube open at one end and closed at the other.

Fig. 4 represents the conclusion of the operation, and shows the holding-back rod projecting entirely through the tube which has been formed and having adhering to its end the small conical fragment C², which is sometimes punched out of the rear end of the blank C.

In another pending application I have described the method of developing a tubular formation from a solid metallic blank solely 30 by the action of diagonally-acting rolls, in which case the necessary holding back of the main body of the blank is effected by the abruptly-converging working-faces of the rolls, and results from the extent to which the diameter of the blank is reduced while passing 35 between the rolls.

The employment of the central holding-back rod as herein described renders it unnecessary to reduce the diameter of the blank to so great 40 an extent as is required when the holding-back effect is obtained only by the bearing of the blank against the convergent faces of the rolls, and it follows, therefore, that when the holding-back bar is employed the solid blank can 45 be transformed into a tube with comparatively little reduction in diameter. The bearing of the end of the holding-back rod against the center of the blank effects a compression of the metal at that point, and thereafter the adjoining 50 metal is pulled radially outward from the center of the blank, and thereby the tubular formation is continued through to the rear end of the blank. The internal diameter of the resulting tubular product will be, to a greater or

less extent, larger than the diameter of the holding-back rod, accordingly as the reduction in the diameter of the blank during its passage through the rolls is greater or smaller.

The holding-back rod may be made of a single bar of metal, or it may be provided with a detachable head, which, if desired, may be of slightly larger diameter than the diameter of the rod D. In Fig. 4 such a head, d², is represented as socketed in the free end of the rod D.

What is claimed as the invention is—

1. In the manufacture of seamless metal tubing, the improvement in the art of transforming solid metal blanks into tubes, which consists in holding back the solid central portion of a suitably-heated blank by means of a holding-back rod while the blank is being subjected to the diagonal rolling and drawing action of two or more rolls, the working-faces of which converge in a prescribed degree and the axes of which are relatively so arranged that a prescribed degree of obliquity is given to the direction in which the working-faces of the rolls act, respectively, upon different sides of the blank, as and for the purposes set forth.

2. In the manufacture of seamless tubing from metal blanks by passing such blanks in a suitably-heated state between the working-faces of diagonally-acting reducing-rolls, the herein-described means for holding back the solid central portion of the heated blank, which consists of a centrally-placed holding-back rod projecting into the space between the rolls, and hence into the tube in process of formation, and abutting at its free end against the solid central portion of the blank, but not touching the interior surface of the tube in process of formation.

3. In diagonal rolling apparatus for imparting a tubular formation to a solid metallic blank, the combination, as herein set forth, of two or more diagonally-acting rolls, the working-faces of which are convergent with a holding-back rod, the free end of which projects into the space between the working-faces of the rolls in position to receive at the proper time the impact of the central portion of a solid blank which is being reduced in diameter and carried forward by the impingement upon its surface of the diagonally-acting rolls.

REINHARD MANNESMANN.
